UNITED STATES PATENT OFFICE

105,981

DESIGN FOR A CONTAINER CAP

William J. Casey, Remington, Ind.

Application March 12, 1936, Serial No. 61,610

Term of patent 14 years

To all whom it may concern:

Be it known that I, William J. Casey, a citizen of the United States, residing at Remington, in the county of Jasper and State of Indiana, have invented a new, original, and ornamental Design for a Container Cap, of which the following is a specification, reference being had to the accompanying drawing, forming part thereof.

I claim:

The ornamental design for a container cap as shown.

WILLIAM J. CASEY.
